UNITED STATES PATENT OFFICE

RAYMOND B. DWYER, OF CHICAGO, ILLINOIS

DESIGN FOR A SCREEN

Application filed December 29, 1930. Serial No. 38,143. Term of patent 14 years.

To all whom it may concern:

Be it known that I, RAYMOND B. DWYER, a citizen of the United States, residing at Chicago, Cook County, Illinois, have invented a new, original, and ornamental Design for Screens, of which the following is a specification, reference being had to the accompanying drawing, forming part thereof.

The figure is a perspective view of a screen, showing my new design.

I claim:

The ornamental design for a screen as shown.

RAYMOND B. DWYER.
